UNITED STATES PATENT OFFICE.

STRAUD K. WOOD, OF HUTCHINSON, KANSAS.

CAR-DOOR SEAL.

Application filed August 17, 1926. Serial No. 129,841.

This invention relates to metal strap seals of the type commonly used in railway freight cars, to seal the door against unauthorized opening, which opening can only 5 take place upon destruction or mutilation of the seal itself.

The principal objects of the invention are to provide a seal of the type described which may be readily and cheaply manufactured, 10 the ends of which may be locked or secured together quickly and which may not again be separated without either destroying the seal or so mutilating the same that such attempt will be readily apparent.

15 To this end the invention contemplates the provision of a metal strap of elongated design, having a head portion bent upon itself a plurality of times and provided with locking tongues and recesses, so that the 20 perforated opposite end of the strap may be inserted between the head folds and securely locked therein and against unlawful separation.

The invention further consists in the novel 25 arrangement, construction and combination of parts hereinafter described and shown in the accompanying drawings, in which:—

Figure 1 is a plan view of a strap made according to my invention, and before folding.

30 Fig. 2 is a view showing the folded strap in use.

Fig. 3 is a perspective view of the partially folded strap.

35 Fig. 4 is a sectional view along the line 4—4 of Fig. 2.

Fig. 5 is a sectional view along the line 5—5 of Fig. 2.

Referring now to the embodiment shown 40 in the drawings, I have shown a seal strap at 1 having a perforated end 2. The opposite end is split so as to form a leg adapted to be folded around itself twice to form folds 3 and 4, part 5 remaining integrally attached to the main portion of the strap and between folds 3 and 4 (see Fig. 3).

45 The fold 4 is provided with a locking tongue 6 having side wings 7 and adapted to extend through aperture 8 in the strap 50 body 1 and be opened out. This secures the folds 3, 4 and 5 to the body in superposed relation.

A cut out tongue 9 having auxiliary

tongue 9^a is provided in fold 4 and a locking aperture as at 10. The perforated end 55 2 of the strap 1 is likewise provided with a punched out tongue 11, and an aperture 13 so that when the end of the strap is inserted between folds 4 and 5, the tongue 9 being bent backwardly until tongue 9^a is out 60 of the path of travel of the strap 2, the tongue 11 of the strap will enter aperture 10 of the fold 4, the tongue 9 of the fold 4 being thus brought opposite the aperture 13 in the end 2 of the strap, and tongue 9^a opposite the 65 registering apertures 14 and 15 in parts 5 and 12 (Fig. 1) respectively. At this stage tongue 9 may be pushed into aperture 13 by pressing on the back of this tongue, the auxiliary tongue 9^a entering the aligned 70 apertures 14 and 15. An offset portion 16 in fold 3 allows the tongue 9^a to project through apertures 14 and 15 to its full extent. These parts will prevent withdrawal 75 of the end of the strap from the locking head.

A side wing 12 as an integral part of the strap body is now to be folded over and tucked between folds 3 and 5. In this position it acts as a reinforcement to the head 80 and prevents the parts from being unfolded to remove the perforated end of the strap. As such the end 2 is encased on all sides in a metal sheath open only at that side through which it is passed between folds 4 and 5.

85 While it is not impossible to unfold the parts and thus remove the end of the strap, yet because of the closeness of the fit it is extremely difficult to do so and such action would so mutilate the parts as to make this 90 tampering apparent.

The strap may bear any desired designation as is well known in seals of this type.

I claim:

1. A car seal comprising a metal strap, 95 said strap having at one end a portion substantially three times the width of the body of the strap, forming wings extending on each side of the longitudinal center of the strap, one of said wings being substantially 100 three times the length of the other wing, an aperture in one of said wings, and a punched out tongue in the opposite end of said strap.

2. A car seal comprising a metal strap, 105 wings extending on each side of the longitudinal center of said strap, one of said

wings being folded first beneath and then on top of itself, the three thicknesses of the material thus formed being then folded toward the longitudinal center of and upon the strap, the loose end of the strap being inserted between two folds of the first mentioned wing, the two mentioned wings being also tucked between two thicknesses of the

first mentioned wing and a tongue in the strap end entering an aperture in the wing to prevent withdrawal of the strap end from the folded wing. ¹⁰

In testimony whereof, I affix my signature.

STRAUD K. WOOD.
